UNITED STATES PATENT OFFICE.

PALMER COX, OF NEW YORK, N. Y.

DESIGN FOR A HANDKERCHIEF, &c.

SPECIFICATION forming part of Design No. 23,093, dated March 6, 1894.

Application filed January 4, 1894. Serial No. 495,708. Term of patent 14 years.

To all whom it may concern:

Be it known that I, PALMER COX, a citizen of the United States, and a resident of the city, county, and State of New York, have invented and produced a new and original Design for Textile Fabrics, of which the following is a specification, reference being had to the accompanying drawing, forming part thereof.

10 The object of my invention is to produce a design such as is not only new and original but also has a pleasing effect to the eye which is peculiar to itself.

15 My design consists of a textile fabric having upon its surface brownie figures as hereinafter described and claimed.

In the drawing:—the figure represents a handkerchief or similar article on which is shown the design.

20 The leading feature of this design consists in the dude brownie which falls entirely within a circular outline or circumference of the center and forms a center of attraction, as it were, when viewed in connection with the other brownie figures which are grouped around as follows: First: On the border of the handkerchief above the dude brownie and arranged at right angles to it, appears an Uncle Sam brownie whose countenance portrays evident astonishment at the "get-up" of the 30 dude. Secondly: On the border, about in line with the dude and on his left appears a Russian brownie whose countenance suggests amazement. Thirdly: On the border, beneath the dude and at right angles to it appears an 35 Esquimau brownie with smiling countenance. Fourthly: On the border, about in line with the dude and on his right appears the principal brownie as if on mischief bent, the border line giving him the appearance of peep- 40 ing around the corner at the dude.

Some of the figures are drawn so as to represent the characteristic dress of a peculiar country thus serving to instruct the young, while the design affords pleasure and amusement to both young and old.

I claim—

The design for a handkerchief or similar article substantially as shown.

PALMER COX.
